TELEVISION SYSTEM

Ray Davis Kell, Haddonleigh, N. J., assignor to
 Radio Corporation of America, a corporation of
 Delaware

Application September 26, 1931, Serial No. 565,226

4 Claims. (CL 178—7.5)

This invention relates to improvements in television systems.

In the operation of television systems, it is important that the background brilliancy of the reproduced picture shall vary in accordance with the brilliancy of the scene being transmitted. For this purpose it has been necessary, heretofore, to continually adjust the apparatus manually.

One of the objects of my invention is to provide an improved television system wherein the degree of background brilliancy of the reproduced picture is faithfully varied automatically in accordance with variations in the intensity of the received picture signals.

Other objects and advantages will hereinafter appear.

In accordance with my invention, use is made of the fact that the background component of a picture bears a definite relation to the amplitude of the picture signals developed during scanning action at the transmitting station. The brilliancy of the picture background is faithfully reproduced at the receiving station by making the direct current or background component of the picture signals proportional to the area of the same in the "white" direction.

More particularly, in accordance with my invention, the received picture signals are applied to the grid of a condenser grid-leak detector to cause the voltage in the plate circuit to vary inversely proportionally to the area of the picture signals in the "white" direction. A background component of the picture is then re-introduced into the control circuit of the receiving apparatus such, for example, as the grid circuit of a cathode ray tube or a control circuit for a neon tube, by applying the plate voltage of the detector to the control circuit of the receiving apparatus.

For the purpose of illustrating my invention, an embodiment thereof is shown in the drawings, wherein

Figure 1 is a diagrammatic view of a television receiving system embodying my invention;

Figs. 2a, 2b, 2c, and 3 are graphical views illustrative of the principle of operation;

Fig. 4 is a fragmentary view similar to Fig. 1, illustrating a modification of my invention;

Fig. 5 is a diagrammatic view of a television transmitter which may be employed in a television system embodying my invention;

Fig. 6 is a side elevational view of the scanning disc used at the transmitting station, looking toward the left in Fig. 5;

Figs. 7 and 8 are enlarged fragmentary views looking toward the left in Fig. 5; and

Figs. 9 and 10 are fragmentary views similar to Fig. 8, illustrating modifications.

The system shown in Fig. 1 is of the same general type as that described in detail in the co-pending application of Arthur W. Vance, Serial No. 544,959, filed June 17, 1931, now Patent 2,137,039, issued November 15, 1938. A suitable radio receiver 10 supplies picture signals to a resistor 11 from which these signals are applied to the control grid 12 of a cathode ray tube 13. For the purpose of causing the cathode ray 14 to scan the fluorescent screen 15, a generator 16 causes a 1200 cycle saw-tooth current-wave to pass through the horizontal deflecting coils 17, while a generator 18 causes a 20 cycle saw-tooth current wave to pass through the vertical deflecting coils 19.

For the purpose of synchronizing the scanning action at the receiver with such action at the transmitter, synchronizing impulses 20 are received at the end of each scanning-line period, 1200 of these impulses being received during each picture-frame period. For the purpose of framing, a single synchronizing impulse, received at the end of each picture-frame period, is substantially greater in amplitude than the others. The adjustment of the generator 16 is such that the same is not responsive to the peak picture signals, but is responsive to the synchronizing impulses 20 of substantially greater amplitude, as indicated in Fig. 2c. The adjustment of the generator 18 is such that the same is responsive only to the single framing impulse which is substantially greater in amplitude than the peak picture signals, and the other synchronizing impulses 20.

The cathode ray tube 13 is supplied with the usual operating potentials, as indicated.

For the purpose of automatically controlling the background brilliancy of the picture, the grid circuit of a suitable condenser grid-leak detector 21 is also supplied with the picture signals from the resistance 11, as shown. The plate voltage of the detector 21 is applied to the control grid 12 of the cathode ray tube through a connection 22 including a suitable resistor 23.

The operation is as follows:

When there is no picture, the only signals received are the synchronizing impulses 20, as shown in Fig. 2a. When these impulses are applied to the grid circuit of the detector 21, there is little or no decrease in the plate current of the detector, as shown by the characteristic curve of the detector in Fig. 3.

When there is a little white in the picture, for example, white letters on a black background,

the received signals are as shown in Fig. 2b. When these signals are applied to the grid circuit of the detector 21, as shown at b in Fig. 3, there is a corresponding slight decrease in the plate current of the detector.

When there is a great deal of white in the picture, the received signals are as shown in Fig. 2c. When these signals are applied to the grid circuit of the detector 21, as shown at c in Fig. 3, there is a corresponding large decrease in the plate current of the detector.

The bias on the control grid 12 and the adjustment of the detector 21 are such that with no picture signal on the grid of the detector, the screen 15 is dark, that is, the cathode ray 14 is cut off.

Upon an increase in the picture signal intensity in the "white" direction, the amount of space current flowing through the detector 21 will decrease correspondingly in the well known manner. The plate voltage of the detector 21, therefore, increases correspondingly and, since this voltage constitutes a bias on the control grid 12 of the cathode ray tube, the negative bias on this tube will decrease to make the screen 15 correspondingly brighter.

From the foregoing, it will be seen that upon an increase in picture signal strength in the positive or "white" direction, the detector 21 causes a corresponding decrease in bias on the cathode ray tube, thereby causing the screen 15 to be more brilliantly illuminated. Upon a decrease in picture signal strength, the detector 21 causes an increase in bias on the tube 13, thereby causing the screen 15 to be illuminated less brilliantly. When there are no picture signals, the adjustment, as stated, is such that the ray 14 is cut off to make the screen 15 dark.

My invention may be embodied in any type of television receiving apparatus by reintroducing into the control circuit thereof the background component of the picture as provided by the detector 21. For example, if the receiver utilizes a neon tube 25, as shown in Fig. 4, the plate circuit of the detector 21 is connected to the grid circuit of a suitable amplifier 26 to the plate circuit of which the tube 25 is connected. The action, then, is the same as that described in connection with Fig. 1, the overall brilliancy of the tube 25 varying directly proportionally to variations in the intensity of the received picture signals.

It will be understood that a transmitter of the same general type as that described in the above mentioned Vance application may be employed for transmitting signals of the character illustrated in Figs. 2a, 2b and 2c. The transmitter described and claimed in the said Vance application is shown in Figs. 5 to 10.

Referring to Fig. 5, a scanning disc 30 is driven by a suitable constant speed motor 31 at 1200 R. P. M., for example, and is interposed in the usual manner between a suitable light source 32 and a lens or lens system 33. A mask 34 is supported between the light source and disc 30.

The disc 30 is provided, for example, with sixty scanning holes A₁—A₆₀, spirally arranged in the usual manner. The holes A₆₀, A₁, and A₂ are plugged, as indicated. The reason for this will be hereinafter explained.

Light reflected from an object 35 excites a photoelectric cell 36, or a bank of such cells, to develop picture signals which are amplified by an amplifier 37 and applied to the input line 38 of a second amplifier 39. The second amplifier

39 is connected, as shown, to a suitable modulator 40 which controls a radio transmitter 41.

For the purpose of synchronizing operations at the transmitting and receiving stations, electrical synchronizing impulses, at the horizontal synchronizing and framing frequencies, are required. The present improved methods and means for developing these two frequencies will now be explained, with reference more particularly to Figs. 6 to 10.

The disc 30 is provided at the outer edge thereof with concentrically arranged holes a₁ to a₆₀, through which light from a light source 42 passes to a photoelectric cell 43, as shown in Fig. 5. A screen 44, provided with an aperture 45 substantially equal in width to that of the disc 30 and the light source 42. A lens 46 may be employed to focus the light on the photoelectric cell.

There being sixty synchronizing holes, the photoelectric cell 43 develops electrical impulses at a horizontal synchronizing frequency of 1200 cycles per second. The impulses or signals at this frequency are amplified by a suitable amplifier 47 and are supplied directly to the input line 38 of the amplifier 39, in parallel with the amplified picture signals.

The width of the opening 48 in the mask 34 is made less than the circumferential distance between adjacent scanning holes, as shown in Fig. 7, to provide for periods during which no picture signals are transmitted. The adjustment of the screen 44 is such that during these periods the synchronizing holes a₁ to a₆₀ move across the aperture 45.

Three picture lines are omitted by plugging holes A₆₀, A₁, and A₂. The synchronizing hole a₁ is equal in width to but is longer than the others, and moves across aperture 45 as the plugged hole A₁ moves back of the right hand edge of opening 48.

The above construction and arrangement provides for development, at a vertical edge of the field of view, of impulses at the horizontal synchronizing frequency, and for development, at a horizontal edge of the field of view, of impulses at the framing frequency. The duration of the framing impulses is equal to that of the other synchronizing impulses because the width of hole a₁ is equal to the width of the other synchronizing holes. The amplitude of the framing impulses, however, is substantially greater because of the greater length of hole a₁.

From the foregoing, it will be seen that although the synchronizing signals are transmitted in the same channel with the picture signals, the former are developed only during periods when the picture signals are cut off, and for this reason interfere in no way with the picture fidelity at the receiving station.

When it is desired that the framing impulses be of greater duration as well as be greater in amplitude than the other synchronizing impulses, the hole a₁ in Figs. 6 and 8 is given the shape shown in Fig. 9. That is, the size and shape of the framing hole in Fig. 9 is such that the same not only moves across aperture 45 for a longer period, but during such movement admits more light to the photoelectric cell 43 than the other synchronizing holes.

If the requirements are such that the framing impulses be of the same amplitude but of greater duration than the other synchronizing impulses, in order to distinguish the former from the latter

at the receiving station, the hole a_1 in Figs. 6 and 8 is given the shape shown in Fig. 10. That is, the size and shape of the framing hole in Fig. 10 is such that the same moves across aperture 45 for a longer period, and during such movement admits the same maximum amount of light to cell 43 as the other synchronizing holes.

The number of stages in amplifiers 37 and 47 is such that the output voltage of amplifier 47 is 180 degrees out of phase with that of amplifier 37, an increase in light intensity on the picture cell 36 causing a corresponding increase, in the positive sense, in the output voltage of amplifier 37. Therefore, when the synchronizing cell 43 is exposed to the light from source 42, there is a sharp increase, in the negative direction, in the output voltage of amplifier 47.

The synchronizing holes a_1 to a_{60} may be disposed on the inside of the scanning holes, if desired. It is also contemplated, if and when found desirable, to employ a separate disc for synchronizing purposes. In such case, the synchronizing disc would be driven by motor 31, and provided with synchronizing holes arranged and formed as described above.

For convenience of explanation, the scanning holes A_{60} , A_1 and A_2 have been described as such, and it has been stated that these holes are plugged to omit several picture lines. In actual practice, however, the disc is not apertured at all at these spots.

While the scanning disc has been described as providing for 60 picture lines, it will be understood that the design may be varied to provide for more or less lines, as might be found desirable for particular conditions. Furthermore, the scanning disc may be replaced by a scanning cylinder or other equivalent rotating means of well known construction. If a scanning cylinder is used, the same may be provided with the synchronizing holes, or a separate cylinder may be employed for the synchronizing action, as explained above in connection with the disc construction.

The amplifiers 37, 39 and 40, and the usual power amplifier forming part of the radio transmitter, are of any well known construction having the following desirable characteristics:

(1) Amplification substantially constant at all required frequencies.

(2) The time-lag in the amplifiers to be either zero or substantially constant at all required frequencies.

(3) The amplification to be substantially constant at all required signal amplitudes. The modulator 40 to give practically constant modulating power over the required frequency range.

10 I claim as my invention:

1. In the art of television wherein received picture signals are applied to an electron beam intensity control electrode of a cathode ray tube to effect reproduction of a view, the method of operation which comprises applying said signals directly to said control electrode, rectifying said signals to produce a control voltage proportional to their area in the white direction and applying said control voltage to said control electrode.

20 2. In a television system, means comprising a cathode ray tube for reproducing a picture, an electron beam intensity control circuit for said tube, means connected to said circuit for supplying the same with picture signals, and a thermionic detector having its input circuit supplied

25 with said signals to rectify them in accordance with their area on the white side of the alternating current axis and having its output circuit connected to said control circuit independently of the connection between said signal-supply means and said control circuit.

3. The invention according to claim 2 wherein the detector is of the grid-leak biased type.

35 4. A television receiver comprising a cathode ray tube having an electron beam intensity control electrode, means for applying picture signal over one path to said electrode for reproducing a view, means positioned in another path for rectifying said picture signal to produce a control voltage that varies in accordance with the area of said signal on the white side of its alternating current axis, and means for applying said control voltage to said control electrode in such sense as to make it more positive in response to an increase in said area.

45 RAY DAVIS KELL.
